TELEPHONE ANSWERING DEVICE HOUSING

Kenneth A. Catto, 4640 NW. Malluer, Portland, Oreg.
97229, and Harold R. Burt, 5550 SW. Cherry Ave.,
Beaverton, Oreg. 97005

Filed Feb. 4, 1971, Ser. No. 112,839

Term of patent 14 years

Int. Cl. D14—03

U.S. Cl. D26—14

Fig. 1

Fig. 2

Fig. 3

FIG. 4

FIG. 5

FIG. 6

FIG. 1 is a perspective view of a telephone answering device housing showing our new design;

FIG. 2 is a top plan view thereof;

FIG. 3 is a front elevation of the housing;

FIG. 4 is a rear elevation of the housing;

FIG. 5 is an elevation of the left side of the housing; and

FIG. 6 is an elevation of the right side of the housing. The broken lines are shown for illustrative purposes only.

We claim:

The ornamental design for a telephone answering device housing, as shown and described.
